[57] CLAIM

The ornamental design for a radio receiver, as shown
and described.

DESCRIPTION

FIG. 1 is a front, top and right side perspective view of
a radio receiver showing our new design;

FIG. 2 is a rear, bottom and left side perspective view
thereof;

FIG. 3 is a top plan view thereof; and

FIG. 4 is a right side elevational view thereof with the
front two rows of rectangular buttons omitted for con-
venience of illustration.

FIG. 1

FIG. 2

FIG. 3

FIG. 4
